CLAIM

The ornamental design for a display panel or screen with an icon, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display panel or screen with an icon showing our new design;

FIG. 2 is a second embodiment thereof;

FIG. 3 is a third embodiment thereof;

FIG. 4 is a fourth embodiment thereof;

FIG. 5 is a fifth embodiment thereof; and,

FIG. 6 is a sixth embodiment thereof.

The dot-dash broken lines show a portion of the display panel and screen and define the boundaries of, but are not included in, the claimed design.

1 Claim, 3 Drawing Sheets
